UNITED STATES PATENT OFFICE

2,161,914

CAR CONSTRUCTION

Otho C. Duryea, Waterbury, Conn., assignor to
 O. C. Duryea Corporation, Wilmington, Del., a
 corporation of Delaware

Application September 15, 1937, Serial No. 164,050

5 Claims. (CL 105—226)

This invention relates to railway car bolsters and more particularly to the construction of the bolster in a railway car equipped with the Duryea underframe, although not restricted to this particular use.

The Duryea underframe, as described for example in United States Patent No. 1,693,194, issued November 27, 1928, to Otho C. Duryea, embodies a draft and buffering column that is movable longitudinally relative to the car body in response to draft and buffering forces to which the car couplers are subjected, suitable cushioning mechanism being interposed between the draft and buffering column and the car body. Hence the transversely extending bolsters adjacent the ends of the car are each provided with openings through which this column extends. In the usual construction the column is formed by spaced channels extending through corresponding spaced openings, the central portion of the bolster which is embraced by the channels being constituted by a strong rigid center brace. It has been proposed to form the laterally extending parts of the bolster together with the center brace in a single casting, as shown in the aforesaid Duryea patent, but this construction, while practicable, requires a large, heavy casting that is difficult to make and heavy and cumbersome to handle. Another construction which has been extensively and successfully used comprises a center brace casting of the general type shown in United States Patent No. 1,938,744, issued December 12, 1933, to Otho C. Duryea, together with riveted laterally extending bolster construction including a bolster cover plate suitably secured to the upper surface of the center brace casting as by rivets. This construction involves some duplication of material due to juxtaposed riveted surfaces, but particularly it involves a large number of riveting operations as well as the possibility that the rivets may rust in service or work loose unless carefully driven.

It is an object of the present invention to avoid the foregoing disadvantages by the provision of novel welded bolster construction which through the elimination of riveting is more economical to manufacture and less liable to imperfection and deterioration but which provides adequate strength and rigidity to withstand hard usage with a minimum of material.

Another object of the invention is to provide novel bolster construction embodying a center brace casting and a bolster cover plate or plates welded into an integral unit.

Other objects of the invention will appear hereinafter as the description proceeds.

One embodiment of the invention has been illustrated in the accompanying drawing but it is to be expressly understood that said drawing is

for purposes of illustration only and is not to be taken as a definition of the limits of the invention, reference being had to the appended claims for this purpose.

In the drawing:

Fig. 1 is an elevation, partly in section, of bolster construction embodying the invention;

Fig. 2 is a vertical section on the line 2—2 of Fig. 1;

Fig. 3 is a partial view of the outer face of 10 the center brace casting; and

Figs. 4 and 5 are details on a large scale showing welded connections.

As shown herein the bolster construction is designed for use with a Duryea underframe of the 15 type disclosed in the aforementioned patents and is accordingly provided with spaced openings 1, 1 through which extend the usual channels 2, 2, these being suitably connected to form a draft and buffering column that is longitudinally movable 20 relative to the car body as above stated. The cushioning mechanism and its connections to the column and car body constitute no part of the present invention and in the interest of simplicity are not shown herein, but it will be 25 understood that any suitable long travel cushioning devices can be employed such as those disclosed for example in the two Duryea patents referred to above.

Disposed between and embraced by the channels 2, 2 is a center brace casting 3 which as shown herein is generally T-shaped, said casting comprising a lower vertical portion intermediate and embraced by the channels 2, 2 and an upper head which extends laterally above the flanges of the channels. This head comprises a lower substantially horizontal floor or wall 4 at a level immediately above the flanges of the channels and vertical stiffening webs extending upwardly therefrom.

As shown in cross section in Fig. 2, outer vertical webs 5 and an intermediate vertical web 6 extend transversely of the center brace casting throughout the width of the horizontal wall 4, and these webs support a bolster cover plate 7 which preferably extends between and is suitably secured to the side sills 8 of the car body as shown in Fig. 1. Each of the vertical webs 5 is provided along its upper edge with a groove 9 whereby these webs may be securely welded to the under side of the cover plate 7 throughout substantially their entire extent transversely of the car. Preferably, an additional weld line is formed along the upper edge of the intermediate vertical web 6, and to this end the cover plate is slotted at 10 and the web 6 is provided along its upper edge with a ridge or bead 11 which projects upwardly into the slot, the cover plate being supported on shoulders 12 along the edges of the bead 11. Preferably, the bead 11 extends 50 55 60

substantially the entire transverse extent of the intermediate vertical web 6 and the slot 10 is of corresponding length. With this construction, the intermediate web 6 can be welded to the cover plate from the top of the plate by a slot weld, whereas the outer webs 5 are welded to the under side of the cover plate by fillet welds.

As shown in cross section in Fig. 1, additional vertical webs 13 extend longitudinally of the center brace casting above the horizontal wall 4, these longitudinal webs being of slightly less height than the transverse webs 5 so that they do not engage the under surface of the cover plate 7. In addition to strengthening the center brace, these longitudinal webs provide means for securing flanged vertical plates 14 which extend longitudinally of the car body through the bolster and define the outer sides of the openings 1, 1. As shown in detail in Fig. 4, each of the webs 13 is provided at its upper edge with a groove 15 and the plates 14 are placed against the webs 13 and secured thereto by fillet welds formed in the grooves 15, the flanges 16 of the plates 14 engaging the under surface of the cover plate 7 to which they may be welded if desired. The lower flanges 17 of the plates 14 engage a bottom cover plate 18 which passes under the channels 2, 2 and the center brace casting 3 and is suitably welded to the latter as by fillet welds along the transverse edges of the plate. The flanges 17 may be welded to the bottom cover plate 18 by providing one or more openings in the cover plate below the flanges or in the flanges above the cover plate, which openings are filled with the weld metal. One such opening is shown in detail at 19 in Fig. 5.

As shown in Fig. 1, the bottom cover plate 18 inclines upwardly on the outer sides of the plates 14 and terminates at the side sills 8 to which it is secured in any suitable manner as by welding. Intermediate the top and bottom cover plates vertical webs or diaphragms 20 may be secured in any suitable manner as by welding. The usual center plate 21 is suitably welded to the bottom cover plate 18, as by providing arms 22 in the center plate and by forming fillet welds at the edges of said arms.

It will be seen that this construction provides a built-up bolster which is welded into an integral rigid unit. By welding the parts together, and particularly by welding the cover plate 7 to the center brace casting to form the upper horizontal wall thereof, casting problems are simplified, expensive riveting operations are eliminated and there is no danger of loose rivets. The transverse weld lines along the webs 5 and 6 provide a construction that is strong and rigid against longitudinally acting draft and buffing forces to which the bolster is subjected in service with a minimum amount of material, and the design is such that the weld lines are easily accessible so that the construction can be manufactured and assembled economically.

While only one embodiment of the invention has been described and illustrated in the drawing, it will be understood that the invention is not limited to this embodiment but is capable of a variety of mechanical expressions and that changes may be made in the form, details of construction and arrangement of parts without departing from the spirit of the invention. Reference is therefore to be had to the appended claims for a definition of the limits of the invention.

What is claimed is:

1. Railway car bolster construction comprising a center brace casting the upper part of which is provided with outer vertical webs and an intermediate vertical web extending transversely of the car body, and a bolster cover plate extending transversely of the car body and supported on said webs, said plate having a transverse slot into which a portion of said intermediate web projects, said outer webs being welded to the under side of said plate and said intermediate web being welded in said slot.

2. Railway car bolster construction having a pair of spaced openings therethrough and comprising a center brace casting between said openings, the upper part of said casting comprising a laterally extending horizontal wall having vertical webs extending transversely of the car body and vertical webs extending longitudinally of the car body, said longitudinal webs having less height than said transverse webs, vertical plates extending longitudinally of the car body through the bolster and defining the outer sides of said openings; said plates being welded to said longitudinal webs, a bolster cover plate supported on the upper edges of said transverse webs and welded thereto, and a bottom cover plate extending transversely on each side of said casting below said openings.

3. Railway car bolster construction having a pair of spaced openings therethrough and comprising a center brace casting between said openings, the upper part of said casting comprising a laterally extending horizontal wall having vertical webs extending transversely of the car body and vertical webs extending longitudinally of the car body, said longitudinal webs having less height than said transverse webs, vertical plates extending longitudinally of the car body through the bolster and defining the outer sides of said openings, said plates being welded to said longitudinal webs, and top and bottom cover plates, the top cover plate being supported on and welded to said transverse webs and the bottom cover plate being welded to the bottom of said casting and to lower flanges on said vertical plates.

4. Railway car bolster construction comprising a center brace casting the upper part of which is provided with outer vertical webs and an intermediate vertical web extending transversely of the car body, top and bottom cover plates extending transversely of the car body on each side of said casting, said bottom cover plate being welded to the bottom of said casting, said top cover plate being supported on said webs and having a transverse slot into which a portion of said intermediate web projects, said outer webs being welded to the under side of said cover plate and said intermediate web being welded in said slot, and vertical plates extending transversely of the car body between said cover plates and welded thereto.

5. In railway car bolster construction, a center brace casting the upper part of which is provided with outer vertical webs and an intermediate vertical web extending transversely of the car body, each of said outer webs having a groove formed along its upper outer edge and said intermediate web having a central bead, and a bolster cover plate supported on said webs and having a slot to receive said bead, said outer webs being welded to the under side to said cover plate by fillet welds in said grooves and said bead being welded in said slot.
